UNITED STATES PATENT OFFICE.

MIKE HUFFMAN, OF DES MOINES, IOWA.

STEAM-BOILER CLEAN-OUT DEVICE.

1,416,207.

Specification of Letters Patent. Patented May 16, 1922.

Application filed September 23, 1919. Serial No. 325,793.

To all whom it may concern:

Be it known that I, MIKE HUFFMAN, a citizen of the United States, and resident of Des Moines, in the county of Polk and State of Iowa, have invented a certain new and useful Steam-Boiler Clean-Out Device, of which the following is a specification.

On October 25, 1910, United States Letters Patent No. 974,064 were issued to me for a new and useful sediment-remover for steam-boilers, which included in its construction a tube or pipe to be permanently inserted in a steam boiler near the bottom thereof, and which was provided with an outlet exterior to the boiler, which outlet was controlled by a valve. The tube was provided with a series of openings capable of being successively uncovered so that when the valve was opened and these openings successively uncovered, the steam pressure within the boiler would exhaust through the valve and carry with it the sediment and scale in the bottom of the boiler adjacent to the uncovered opening, thus effecting a cleaning of the boiler.

My present invention consists in the nature of an improvement upon the type of boiler cleaner disclosed in my said patent. In my present invention, instead of a series of openings I have provided continuous slots in both the stationary and rotatable tubes within the boiler, one of which is spirally arranged so that during the rotation of one of the tubes the straight slot and the spiral slot will register or coincide at progressively advancing points, so that the water can blow off through the slots throughout the entire length of the boiler.

More specifically it is my object to provide means whereby the rotation of the movable tube is made automatic and capable of operation by the pressure of the outgoing water, so that the water blows off through the tubes progressively from one end of the boiler to the other in a rapid manner, producing considerable agitation within the boiler to stir up and remove sediment more perfectly than was possible with the construction described in my said patent.

A further object is to provide means for automatically cleaning the registering slots in the tubes to prevent them from being clogged by sediment or scale.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a central, longitudinal, vertical, sectional view of a device embodying my invention when applied to a portion of a steam boiler.

Figure 2 shows an inverted plan view of the stationary and rotatable blow-off tubes, showing by dotted lines the position of the spiral slot.

Figure 3 shows a detail view of the automatic slot cleaning device, with the adjacent portions of the tubes through which it is passed, illustrated in section.

Figure 4 shows a sectional view on the line 4—4 of Figure 3; and

Figure 5 shows a sectional view on the line 5—5 of Figure 1.

Referring to the accompanying drawings, I have used the reference numeral 10 to indicate that portion of the steam boiler illustrated in the drawings.

My improved cleaning device may be used in the nature of an attachment to be applied to steam boilers, or it may be furnished with new steam boilers, as desired.

In one end of the boiler I form an opening through which the clean-out tubes may be inserted, and adjacent to this opening is a detachable screw-threaded cover plate 11 which may be secured by bolts 12 to 90 the boiler. The outer or stationary clean-out tube is indicated by the numeral 13, and is provided with a cap at one end to close the end, and its other end is screwed to the plate 11, thus supporting it in position 95 within the boiler. This tube is provided, as clearly shown in Figure 2, with a longitudinally arranged slot 14 in its under side. On the end of this tube that projects beyond the boiler, I have provided a stuffing box 100 to prevent leakage.

Rotatably mounted within the outer tube 13 is the inner tube 16, provided with a spirally arranged slot 17. This inner tube is capable of free rotation within the stationary outer tube, and is introduced at its end outside of the boiler into a valve 18, there being a stuffing box 19 connecting the

valve with the said inner tube to prevent leakage and to permit the inner tube to freely rotate within the valve.

For the purpose of automatically rotating the inner tube I have provided on the interior thereof a spiral blade 20 fixed in position by frictional contact caused by forcing the said spiral member longitudinally in the said tube and so arranged that when water enters the interior of the tube 16 through its slot, this water will travel rapidly through the tube 16 and the valve 18, the said blade 20 will cause the inner tube to rotate due to boiler pressure. Obviously, during this rotation the spiral slot 17 and the straight slot 14 will come into coinciding or registering positions progressively throughout the length of the tubes, so that at times the water from the interior of the boiler will pass through the registering slots at one end and then progressively through the tubes at the points where the slots coincide or register, until the other ends of the tubes are reached, so that when it is desired to clean out a boiler it is only necessary for the operator to open the valve 18, whereupon the steam pressure in the interior of the boiler will bear upon the spiral blade 20 and cause it to turn and carry with it the inner tube.

In the event that, for any reason, the inner tube should fail to start properly, I have provided a handle 20 detachably secured to the inner tube by the set screw 22, which handle may be turned until the inner tube is capable of free movement, whereupon the movement will be continued by the action of the water upon the spiral blade.

I have also provided means for automatically cleaning the slots which sometimes become clogged by sediment or scale. For this purpose I have provided a tube 23 having flanged ends 24 and a roller 25 surrounding the tube 23 between the heads 24. This tube and its roller are extended through the slots 14 and 17 at the point where they register or coincide, and obviously, as the inner tube is rotated, and the blow-out roller, the tube 23 will be moved longitudinally of the tubes 23 and 16, and during this movement any sediment or scale that may have become lodged in the slots will be removed, while the water will enter the tube 16 through the opening of the tube 23, as the said tube 23 is moved longitudinally in the slots 14 and 17.

I claim as my invention:

1. In a device of the class described, the combination of an outer stationary tube and an inner rotatable tube, said tubes being provided with openings that are capable of registering or coinciding at different parts of the tubes during the time that the inner tube is rotated, and means connected to the

said inner tube, to be acted on by the water escaping through the said inner tube, for causing said inner tube to rotate.

2. In a device of the class described, the combination of an outer stationary tube and an inner rotatable tube, said tubes being provided with openings that are capable of registering or coinciding at different parts of the tubes during the time that the inner tube is rotated, means connected to the said inner tube, to be acted on by the water escaping through it, for causing said inner tube to rotate, and a shut-off valve applied to the end of the inner tube projected beyond the boiler, whereby upon the opening of said valve the action of the escaping water through said valve and inner tube will cause the inner tube to automatically rotate.

3. In a device of the class described, the combination of an outer stationary tube and an inner rotatable tube, said tubes being provided with openings that are capable of registering or coinciding at different parts of the tubes during the time that the inner tube is rotated, means connected to the said inner tube, to be acted on by the water escaping through it, for causing said inner tube to rotate, a shut-off valve applied to the end of the inner tube projected beyond the boiler, whereby upon the opening of said valve the action of the escaping water through said valve and inner tube will cause the inner tube to automatically rotate, and a lever applied to the rotatable inner tube, whereby it may be manually turned.

4. In a device of the character described, the combination of an inner and an outer tube, one of which is rotatable relative to the other, said tubes being provided, one with a straight slot and the other with a spiral slot, and a movable cleaning device inserted through the registering slots of said tubes, and capable of being advanced longitudinally of the tubes when the rotatable tube is turned.

5. In a device of the character described, the combination of an inner and an outer tube, one of which is rotatable relative to the other, said tubes being provided, one with a straight slot and the other with a spiral slot, and a movable cleaning device inserted through the registering slots of said tubes, and capable of being advanced longitudinally of the tubes when the rotatable tube is turned, said device comprising a headed tube passed through the said tubes, and a roller on said headed tube, between the heads thereof, and designed to engage the edges of the slots of the first mentioned tubes, for the purposes stated.

Des Moines, Iowa, July 3, 1919.

MIKE HUFFMAN.
